UNITED STATES PATENT OFFICE.

CHARLES S. BATDORF, OF BROOKLYN, NEW YORK.

MACHINE FOR MAKING PAPER CUPS.

1,420,808.

Specification of Letters Patent. Patented June 27, 1922.

Application filed November 7, 1918, Serial No. 261,445. Renewed December 13, 1921. Serial No. 522,145.

To all whom it may concern:

Be it known that I, CHARLES S. BATDORF, a citizen of the United States, and a resident of Brooklyn, in the county of Kings 5 and State of New York, have invented certain new and useful Improvements in Machines for Making Paper Cups, of which the following is a specification.

The invention relates to the manufacture of paper cups, such as are used for drinking and other purposes, and it consists in the novel features, organization and structure hereinafter described and claimed.

One object of my invention is to provide 15 a reasonably small and comparatively inexpensive machine capable of use by the owner thereof for making a paper cup at anytime such cup might be desired. One special purpose accomplished by the invention 20 is the fact that the paper after having been introduced in the form of a reel to the machine, does not require to be handled at all and is protected as far as possible from contamination of any kind. The machine 25 comprises a female die, means for feeding a proper length of the paper across the same, means for cutting off such length from the body of the strip, a male die for driving the paper into the female die and 30 a cutting die for turning over the upper edges of the paper and trimming off the surplus portions of the paper around the lip of the cup. The strip of paper wound into a reel is delivered bodily to the machine 35 and is not again touched by the human hand, but confined within a closed casing, and the lengths for the separate cups are fed from this strip, and one feature of my invention is that with my machine I may 40 employ a strip of paper of uniform width, such as may be easily made, in lieu of employing paper blanks which have been cut by dies and handled before being delivered to the machine. One of my aims is to produce 45 a machine and manufacture cups thereon without the paper or the cups becoming contaminated in any way. When a cup has been made it may be removed from the machine by the hand of the person desiring 50 to use it.

The invention will be fully understood from the detailed description hereinafter presented, reference being had to the accompanying drawings, in which:

55 Fig. 1 is a vertical longitudinal section through a machine constructed in accord-

ance with and embodying the invention, the mechanism being shown in a partly operated position with the requisite length of paper fed across the female die and cut from the 60 body portion of the paper and the male die as having reached a position preparatory to driving the cut off section of the paper into said female die;

Fig. 2 is a detailed side elevation, partly 65 broken away and partly in section, illustrating the mechanism for compelling a full down stroke and a full up stroke of the mechanism connected with the male die features;

70 Fig. 3 is a view corresponding substantially with Fig. 1, but illustrating the final operation of the mechanism in the formation of a cup and prior to the male die features being restored to their initial position, which is indicated by the dotted lines;

Fig. 4 is a top view, partly in section, of 75 the machine, looking down on Fig. 3, the sectional portion being through a casing enclosing a part of the superstructure of the machine;

Fig. 5 is a sectional view through a portion of the machine, taken on the dotted line 5—5 of Fig. 4 and illustrating more particularly the coin mechanism required, when 80 desired, for the operation of the machine;

Fig. 6 is a corresponding view of the same, taken on the dotted line 6—6 of Fig. 4;

Fig. 7 is a transverse section, partly 85 broken away, through the machine, taken on the dotted line 7—7 of Fig. 4;

Fig. 8 is a transverse section through a portion of the machine, taken on the dotted line 8—8 of Fig. 4;

Fig. 9 is a vertical transverse section 95 through the cup formed on the machine, the dotted lines indicating the upper edges of the paper formation prior to the same being folded outwardly and downwardly and trimmed, and

100 Fig. 10 is a side elevation of the completed cup.

In the drawings, 15 designates a suitable bed-plate mounted upon customary supports 16 and having mounted on it the various 105 features constituting the essential portions of my invention. Upon the rear end of the bed-plate 15 are suitable standards 17, 18, 19 and 20 and in the upper ends of these standards is mounted a transverse shaft 21 upon 110 which are mounted a frame 22 and an operating lever 23, the frame 22 being rigid with

the shaft 21 and the operating lever 23 being pivotally mounted on said shaft. The frame 22 comprises two arms 24 integral at their front ends with a sleeve or collar 25, and the 5 operating lever 23 is disposed between the arms 24 and during a portion of the operation of the machine moves therewith, while during another portion of the operation of the machine the lever 23 has a movement 10 independent of the frame 22, said frame then being stationary. Upon the shaft 21 is coiled a spring 26 which engages the lower edge of the actuating lever 23 and the upper rear edges of the arms 24 of the 15 frame 22, and this spring 26 serves to tie the lever 23 and frame 22 together in a manner permitting of the simultaneous movement of said lever and frame during a portion of the operation of the machine and allowing 20 said lever to have an independent final movement, while the frame 22 is stationary.

The frame 22 has at the lower side of its members 24 downwardly projecting presser arms 27, which, as hereinafter explained, are 25 utilized in connection with a cutter bar 28 for cutting off the proper sections 29 of paper from the body portion 30 of the paper for the formation of a cup, and the frame 22 is formed at the hub of one of its members 30 24 with stop lugs 31, 32 adapted to engage a pin 33 on the standard 18 for arresting said frame 22 in its two positions, the lug 31 engaging said pin when the frame 22 is in its upper initial position indicated by 35 dotted lines in Fig. 3 and the lug 32 engaging said pin when said frame 22 reaches its lower position indicated by solid lines in Fig. 1.

The actuating lever 23 is swiveled on the 40 shaft 21 and has an operating handle 34 by which said lever may be manually operated, and at the rear of the handle 34 said actuating lever 23 is formed with a ring or band 35 which encompasses a cutting die 36 45 of inverted cup form and having a shank 37 which extends through an opening in the sleeve or collar 25 formed on the front end of the frame 22. The die 36 has a lower cutting edge 38 and it is connected with the ring 50 or band 35 by means of studs 39 on the sides thereof entering slots 40 in the sides of said ring or band 35, as may be clearly understood on reference to Figs. 1, 4 and 8.

The cutting die 36 carries a plunger or 55 male die 41 whose body portion represents the interior outline of the cup to be formed, and said plunger or male die 41 is connected with the cutting die 36 by means of pins 42 extending laterally from the upper side portions of said plunger or male die 41 and confined within vertically elongated slots 43 formed in the sides of said cutting die 36. The plunger or male die 41 is formed or provided 60 at its upper end with a central vertical stem 44 which projects upwardly into a

socket 45 formed in the stem 37 of the cutting die 36, and around the stem 44 is placed a coiled spring 46 which bears against the upper end of the plunger or die 41 and against a shoulder 47 formed within the 70 stem 37 by the enlargement of the lower end of the socket 45 to accommodate said spring 46. The spring 46 is of some rigidity and normally acts to retain the plunger or male die 41 in the position in which it is shown 75 in Fig. 1 with the pins 42 at the lower ends of the slots 43. When the actuating lever 23 is given a movement independent of that of the die 41, the spring 46 becomes compressed between the upper end of the plunger or male die 41 and the shoulder 47, and this independent movement of said actuating lever 23 takes place immediately after the mechanism has been sufficiently operated 80 for driving the plunger or male die 41 downwardly against the cut off section 29 of the paper and causes the same to force said section into the female die 48, the further and independent movement of said lever 23 then taking place for effecting the descent of the 85 cutting die 36 for turning over that portion of the paper which projects above the die 48 and cutting off the surplus part thereof, so as to leave a finished cup in the die 48, the cutting die 36 then taking the position 90 with relation to the male die 41 shown in Fig. 3. The spring 46 is sufficiently rigid not to compress to any material extent during the downward movement of the die or plunger 41 to force the paper into the female 95 die 48, and during this action the plunger or male die 41 and cutting die 36 maintain 100 their relation to one another shown in Fig. 1, the pins 42 remaining at the lower ends 105 of the slots 43. When, however, the plunger or male die 41 has completed its downward movement the lever 23 is given its independent movement to carry the cutting die 36 downwardly to complete the formation of the upper edge of the cup, the slots 43 then 110 riding downwardly on the pins 42 until finally the said pins are at the upper ends of said slots, as shown in Fig. 3. When the cutting die 36 is having its independent downward movement for finishing off the 115 upper edge of the cup, the stem 37 thereof slides downwardly through the collar 25 at the front end of the frame 22 and compresses the spring 46. After the die 36 has performed its duty and the pressure on the 120 handle end of the lever 23 is relaxed, the spring 46 returns to its normal condition and effects the upward movement of the die 36, the lever 23 and its parts continuing to move upwardly with the assistance of the 125 spring 26 until said parts take the relation to the collar 25 in which they are shown in Fig. 1, the pins 42 drawing the die 41 upwardly from the die 48. The lower edge of the die 36 is formed with an inner annular 130

recess 49 and below this recess with another annular recess 50 which is of greater diameter than the recess 49 and at the upper edge of which is formed a shoulder 51. The cutting edge 38 is at the lower edge of the recess 50. The lower portion of the cutting die 36 is adapted to the construction of the upper edge of the female die 48, which has a thin portion 52, over which the recess 49 passes when the die 36 is moved downwardly, and the folded over upper edge of the paper in the cup formation lies along the outer side of the said portion 52 and within the recess 49, as shown in Fig. 3. The shoulder 51 at the lower end of the recess 49 is adapted to seat on an annular shoulder 53 which is formed around the upper exterior portion of the female die 48, and the extreme cutting edge 38 of the die 36 is adapted to trim off the surplus portion of the paper against the outer angular edge of the shoulder 53.

The initial normal inoperated position of the actuating lever 23 and frame 22 is that illustrated in Fig. 3 by dotted lines and the final operated position of said parts is that shown by solid lines in Fig. 3.

The reel of paper 30 from which the cups are to be formed is held in a casing 54 below the bed-plate 15, and the casing 54 will preferably have downwardly converging bottom sections so that the reel of paper may be centralized and left loose within said casing. The strip of paper from the reel 30 is extended upwardly through an opening or slot 55 in the bed-plate 15 and then passed between two rollers, preferably rubber faced, 56, 57, which extend transversely across the machine and are mounted in suitable bracket arms 58 extending forwardly from the end standards 17, 20. The roller 57 is driven and by its pressure toward the roller 56 rotates said roller so that both rollers rotate against each other for the purpose of drawing the paper strip forwardly over a suitable table 59 provided above the bed-plate 15. The roller 57 is driven or given its proper rotary movement by means of a segment 60 secured on the shaft 21 and adapted at the proper time to engage a pinion 61 which is loose on the shaft 62 of the roller 57, and said pinion wheel 61 is rigid with a ratchet wheel 63, which is engaged by a pawl 64 pivotally held on a disk 65 which is rigidly secured on the said shaft 62 of the roller 57. When the segment 60 is moved downwardly from the dotted position shown in Fig. 3, it engages the pinion wheel 61 and rotates the same, and the motion of said wheel is communicated by the ratchet wheel 63 to the pawl 64 and disk 65, with the result that the shaft 62 and roller 57 will be rotated and a proper section 29 of the strip of paper will be fed forwardly over the table 59 and across the top of the female die 48. On the upward movement of the segment 60 from its posi-

tion shown by full lines in Fig. 3 to that illustrated by dotted lines in Fig. 3, said segment will again engage the pinion wheel 61 and at this time the ratchet wheel 63 will ride below the pawl 64 without communicating its motion to the disk 65 or shaft 62, this arrangement being for the purpose of permitting the rollers 56, 57 to stand idle while the operative mechanism is being returned to its initial position, shown by dotted lines 75 in Fig. 3.

The first step in the operation of the machine when the actuating lever 23 is pulled downwardly, is that performed by the segment 60 in feeding forwardly over the table 80 59 and female die 48 just the requisite section or length of the paper for one cup, and immediately thereafter and after the segment 60 has left the pinion wheel 61 and the rollers 56, 57 are stationary, the presser arms 85 27 descend against the cutter bar 28 for cutting off the section 29 of the paper, said cutter bar 28 carrying a knife 66 which descends through the paper and into a slot 67 in the table 59, and said blade cooperating 90 with the upper edge of the table 59 at the slot 57 to cut off the paper smoothly.

The paper during its movement is guided by the longitudinal guides 68 formed of sheet metal and being located at each edge 95 of the path of the strip, as shown in Fig. 4. The guides 68 constitute a portion of a sheet metal frame at whose inner end is a transverse section 69 connecting the guide members 68 and below which the paper is caused 100 to travel. At the front of the blade 66, the sheet metal of said transverse connecting section 69 is flared upwardly, as shown in Fig. 1, so as to serve as an effectual entrance slot for the end of the paper fed forwardly 105 by the rollers 56, 57, and said section 69 is slotted in line with the aforesaid slot 67 so as to provide for the descent of the blade 66 through the paper.

The cutter bar 28 is a plain transverse bar 110 carrying the blade 66 and mounted at its ends between vertical guides 70 and upon coiled springs 71 which serve to move the bar 28 upwardly to its initial position after the presser arms 27 have receded upwardly 115 from the same. The ends of the bar 28 are provided with slots 72 (Fig. 7) to receive pins 73 extending into them from the vertical guides 70, said slots and pins serving to limit the movement of said bar.

Since it is one purpose of this invention to provide for the accurate feeding of one section 29 of paper for a cup at the commencement of each down stroke of the frame 22 and actuating lever 23, it is desirable that 125 when said frame and lever are moved, there should be a complete down stroke and a complete up stroke thereof, and to this end I provide means for preventing the return of the frame 22 and lever 23 after the same 130

have started downwardly until they have completed their full movement and likewise I provide means whereby when said frame and lever have been started upwardly to 5 their initial position shown by dotted lines in Fig. 3 they must be returned absolutely to such position before they can be started downwardly again; and the means I provide for accomplishing these purposes are 10 more particularly illustrated in Figs. 2, 4 and 7 and comprise a stationary ratchet bar 74 secured against the standard 17, a ratchet bar 75 pivotally secured to said standard and a pawl 76 which is pivotally secured to 15 a disk 77 which is rigid on the shaft 21. When the frame 22 and lever 23 are started downwardly, the pawl 76 will ride up the ratchet bar 75 and will not leave said ratchet bar, by dropping over the front end of the 20 same, until about the end of the down stroke of the frame 22 and lever 23, at which time the pawl 76 will fall from over the forward end of the ratchet bar 75 and enter into engagement with the ratchet bar 74, as I indicate by dotted lines in Fig. 2. Upon the 25 upstroke of the frame 22 and actuating lever 23, the pawl 76 will ride up the ratchet bar 74 until it has attained the dotted position in which it is indicated at the upper end of said 30 bar, in which position it will lock the frame 22 in its initial position. The frame 22 cannot be returned downwardly until after it has reached its initial position because of the engagement of the pawl 76 with the bar 35 74. I pivot the bar 75 so that as the frame 22 is reaching its initial position, the pawl 76 may ride under and lift said bar 75 so that the pawl may reach its position shown by dotted lines at the right hand side of Fig. 2. 40 The ratchet bar 75 prevents an upward movement of the frame 22 after said frame has started downwardly, and the ratchet bar 74 prevents a downward movement of said frame 22 after the same has been started 45 upwardly.

It may be desirable to apply to the machine means by which it can only be operated on the introduction of a proper coin to pay for the cup to be made, although my invention is not limited to the application thereto of any such coin controlling mechanism. I, however, illustrate suitable means whereby the shaft 21 cannot be operated from the frame 22 until a proper coin has been introduced to said shaft. In Figs. 4 to 7 inclusive I illustrate the coin controlled mechanism, which is of very simple nature and comprises a slot or socket 78 formed in the shaft 21 to receive a coin 79 from a coin slot 80 formed in the enclosing casing 81, a pivoted dog 82 secured to the standard 20, a recess 83 formed in the shaft 21 to receive the detent of said dog, an arm 84 extending laterally from the free end of the dog 82 and 65 lying adjacent to the entrance to the coin

socket 78, and a lug 85 preferably formed on the shaft 21 at one side of the entering end of the socket 78, as shown in Fig. 5, to serve as a support for the coin 79. If no coin is introduced through the coin slot 80, the detent 86 of the dog 82 will, by engaging the shoulder at the rear end of the recess 83 prevent the shaft 21 from being rotated, and this of course would prevent the frame 22 from being pulled downwardly to form the 75 cup. When a coin 79 is introduced into the socket 78 of the shaft 21 and the frame 22 is started on its downward movement, the coin will engage the arm 84 of the dog 82 and lift said dog to a position in which its 80 detent 86 will be outside of the recess 83, and at such time the shaft 21 may continue in rotation and the frame 22 continue in its downward movement. After the shaft 21 has made a sufficient rotary movement, the 85 coin 79 will fall from the socket 78 and be caught within the general casing of the machine and upon the bed-plate 15, whence at some convenient time it may be removed.

The casing 81 is of rectangular outline 90 and will enclose as much of the machine as may be expedient so as to protect, as far as possible, the operative parts from dust or other contamination. The roll of paper is well protected by the casing 54, and it will 95 be seen that only enough paper for one cup is exposed over the die 48 and that it only becomes exposed when a cup is to be immediately formed therefrom. The paper is not handled manually at all after it has once 100 been introduced to the machine, and the finished cup may be removed from the machine by the hand of the person desiring to use it.

I number the cup 87 and the downwardly pressed lip around the mouth thereof is indicated by the number 88.

The operation of the machine will largely be understood from the description hereinbefore presented, and hence but slight further explanation of such operation is necessary. The initial position of the frame or arm 22, actuating arm 23 and segment 60 is indicated by dotted lines in Fig. 3. The paper from the reel 30 has its free end caught between the rollers 56, 57, and when it is 110 desired to form a cup the operator will pull downwardly on the frame 22 and arm 23 and this will result in the said arm 23 and frame 22 turning downwardly and forwardly, with the result that the segment 60 115 will be carried against the pinion wheel 61 and cause the rollers 56, 57 to feed forwardly between the guides 68 a sufficient length of the paper, which may be called a section 29, across the female die 48 for the formation 120 thereof of one cup. The segment 60 leaves the pinion-wheel 61 before the frame 22 and arm 23 have completed their downward movement, and after the segment 60 passes 125 from engagement with the pinion-wheel 61, 130

the presser arms 27 descend against the cutter bar 28 and the knife blade 66 severs the section 29 of paper at the slot 67 in the bed-plate or table 59. The continued downward movement of the actuating arm 23 results in the male die 41 being pressed downwardly against the paper section 29 and forcing the paper into the female die 48, the edge portions of the paper standing upwardly above said female die, as indicated by dotted lines in Fig. 9, and thereupon the continued downward movement of the arm 23 independently of the frame 22 effects the downward movement of the cutting die 36 against the upwardly projecting portions of the paper around the top of the die 48, and this results in said projecting portions of the paper being folded down around the upper edge of the female die 48 to form the lip 88 around the cup and in the surplus portions of the paper being cut off so as to leave a lip 88 having a uniform edge. In Fig. 3 I show the cutting die 36 in its lower position. The body portion of the male die tapers downwardly and is adapted to fit with reasonable closeness within the female die 48, whose side walls extend downwardly on converging lines, and due to the formation of said male and female dies that portion of the paper which projects upwardly above the die 48, as shown by the dotted lines in Fig. 9, also flares outwardly and permits the entrance to the inner side thereof of the lower portions of the cutting die 36, which portions perform the duty as aforesaid of folding the said projecting portion of the paper outwardly and downwardly and cutting the surplus therefrom. The surplus paper in the sides of the cup is flattened or plaited against the walls of the die 48. After the cup has been formed, the spring 46 which becomes compressed during the said independent movement of the arm 23, will, upon pressure being relaxed from the handle 34, move the cutting die 36 upwardly, and thereafter the arm 23 may be restored to its initial position, carrying the several operative parts to the position shown by dotted lines in Fig. 3. The finished cup may then be removed from the die 48. The operation is a simple one and only requires, after the paper 30 is in position, one complete downward movement of the frame 22 and actuating arm 23 to feed the length of the paper across the female die, cut off that length, depress the paper into the female die 48 and form the lip 88 on the cup and trim the edges of the paper around said lip. It has already been explained that when the frame 22 is started downwardly it is compelled to have a complete downward movement before it starts upwardly again and that after the said frame has been started upwardly, said frame must be carried to its extreme upper position before it can be started downwardly again. The coin-controlled mechanism may or may not be used, as may be preferred. The machine is small, comparatively inexpensive to build, sanitary and adapted to be used by the owner for making a cup at any time a cup should be desired. I have described the machine as being used for making what are commonly called paper drinking cups, but cups or receptacles other than for drinking purposes may be produced with the use of my invention.

What I claim as my invention and desire to secure by Letters-Patent, is:

1. In a machine of the character described, a female die having converging walls over which paper for a cup may be placed, a male die having tapered walls for forcing the paper into said female die and leaving a part of the paper projecting upwardly and flared outwardly around the edges of the same, a cutting die around the upper portion of said male die adapted to enter within and engage said upwardly projecting portion of the paper and fold the same downwardly around the upper end of the female die to form a lip in the cup and cut off the surplus portion of the paper around said lip, and means for effecting the operation of said male and cutting dies.
2. In a machine of the character described, a female die over which paper for a cup may be placed, a male die for forcing the paper into said female die and leaving a part of the paper projecting upwardly around the edges of the same, a cutting die around the upper portion of said male die adapted to engage said upwardly projecting portion of the paper and fold the same downwardly around the upper end of the female die to form a lip on the cup and cut off the surplus portion of the paper around said lip, a spring interposed between said male die and cutting die and permitting said cutting die to have an independent movement imparted to it for forming said lip and cutting off the surplus portion of the paper after the male die has become seated in said female die, and means for effecting the operation of said male and cutting dies.
3. In a machine of the character described, a female die over which paper for a cup may be placed, a male die for forcing the paper into said female die and leaving a part of the paper projecting upwardly around the edges of the same, a cutting die around the upper portion of said male die adapted to engage said upwardly projecting portion of the paper and fold the same downwardly around the upper end of the female die to form a lip on the cup and cut off the surplus portion of the paper around said lip, and means for effecting the operation of said male and cutting dies, said female die having an external annular

recess, with an outwardly offset shoulder, around its upper end to receive the paper for said lip, and said cutting die having within its lower end an annular recess to 5 pass upon and encompass the upper end of the female die and a shoulder to match the shoulder on said female die.

4. In a machine of the character described, a female die over which paper for a cup 10 may be placed, a male die for forcing the paper into said female die and leaving a part of the paper projecting upwardly around the edges of the same, a cutting die around the upper portion of said male die 15 adapted to engage said upwardly projecting portion of the paper and fold the same downwardly around the upper end of the female die to form a lip on the cup and cut off the surplus portion of the paper 20 around said lip, a spring interposed between said male die and cutting die and permitting said cutting die to have an independent movement imparted to it for forming said lip and cutting off the surplus portion of the paper 25 after the male die has become seated in said female die, and means for effecting the operation of said male and cutting dies, said female die having an external annular recess, with an outwardly offset shoulder, 30 around its upper end to receive the paper for said lip, and said cutting die having within its lower end an annular recess to pass upon and encompass the upper end of the female die and a shoulder to match the 35 shoulder on said female die.

5. In a machine of the character described, a female die having converging walls, over which paper for a cup may be placed, a male die having tapered walls for forcing 40 the paper into said female die and leaving a part of the paper projecting upwardly and flared outwardly around the edges of the same, a third die encompassing the upper portion of and carrying said male die 45 and adapted to enter within and engage said upwardly projecting portion of the paper and fold the same downwardly around the upper end of the female die to form a lip on the cup and cut off the surplus portion 50 of the paper around said lip, a spring interposed between said male die and third die and permitting said third die to have an independent movement imparted to it for forming said lip after the male die has 55 become seated in said female die, and a manually operative lever connected with said male die and third die for effecting the operation of the same.

6. In a machine of the character described, a female die over which paper for a cup 60 may be placed, a male die for forcing the paper into said female die and leaving a part of the paper projecting upwardly around the edges of the same, a cutting die 65 around the upper portion of said male die

adapted to engage said upwardly projecting portion of the paper and fold the same downwardly around the upper end of the female die to form a lip on the cup and cut off the surplus portion of the paper around 70 said lip, and manually operative means connected with said male and cutting dies for effecting the operation of the same.

7. In a machine of the character described, a female die over which paper for a cup 75 may be placed, a male die for forcing the paper into said female die and leaving a part of the paper projecting upwardly around the edges of the same, a cutting die around the upper portion of said male die 80 and having a pin and slot connection therewith and adapted to engage said upwardly projecting portion of the paper and fold the same downwardly around the upper end of the female die to form a lip on the cup 85 and cut off the surplus portion of the paper around said lip, a stem on said cutting die containing a vertical chamber and a shoulder, a stem on said male die entering said 90 chamber, a spring interposed within said chamber between and engaging said shoulder and said male die and permitting said cutting die to have an independent movement imparted to it after the male die has 95 become seated in said female die, and means for effecting the operation of the male and cutting dies.

8. In a machine of the character described, means for supporting a reel of paper, a female die, means for feeding a 100 definite length of the paper for a cup over said die, means for severing said length from the body of the paper, a male die for forcing the cut off paper into said female die and leaving a part of the paper projecting upwardly around the edges of the same, a cutting die around the upper portion of said male die adapted to engage said upwardly projecting portion of the paper and fold the same downwardly to form a lip on the cup 105 and cut off the surplus portion of the paper around said lip, and manually operative means adapted on a single stroke thereof to effect all the operations hereinbefore indicated. 110

9. In a machine of the character described, means for supporting a reel of paper, female and male dies for forming a cup, means for feeding a definite length of the paper for a cup over the female die, means for severing such length from the body of the paper, and manually operative means for, on a single stroke thereof, actuating the mechanisms comprising a shaft, a segment to actuate the feeding means, an arm fastened on said shaft and carrying means for actuating said severing means, and an actuating lever on said shaft and having a spring connection with said arm so as to be capable of movement therewith and also in- 115 120 125 130

dependently thereof and carrying the male die.

10. In a machine of the character described, a female die over which paper for a cup may be placed, a male die for forcing the paper into said female die and leaving a part of the paper projecting upwardly around the edges of the same, a cutting die around the upper portion of said male die 10 adapted to engage said upwardly projecting portion of the paper and fold the same downwardly around the upper end of the female die to form a lip on the cup and cut off the surplus portion of the paper around 15 said lip, a spring interposed between said male die and cutting die and permitting said cutting die to have an independent movement imparted to it for forming said lip and cutting off the surplus portion of the

paper after the male die has become seated 20 in said female die, and means for effecting the operation of said male and cutting dies, comprising a shaft, an arm thereon having at its outer end a guiding collar, and an actuating lever on said shaft having a spring 25 connection with said arm so as to be capable of movement therewith and also independently thereof and pivotally connected with said cutting die, said male die having a loose connection with said cutting die and said 30 cutting die having a stem within said collar.

Signed at New York city, in the county of New York and State of New York, this 4th day of November, A. D. 1918.

CHARLES S. BATDORF.
